UNITED STATES PATENT OFFICE.

LYMAN C. HUFF, OF CHICAGO, ILLINOIS. ASSIGNOR TO UNIVERSAL OIL PRODUCTS COMPANY, OF CHICAGO, ILLINOIS, A CORPORATION OF SOUTH DAKOTA.

APPARATUS FOR REMOVING CARBONACEOUS MATERIAL FROM OIL APPARATUS.

Application filed January 26, 1923. Serial No. 614,954.

To all whom it may concern:

Be it known that I, LYMAN C. HUFF, a citizen of the United States, and a resident of the city of Chicago, county of Cook, and State of Illinois, have invented certain new and useful Improvements in Apparatus for Removing Carbonaceous Material from Oil Apparatus, of which the following is a specification.

10 This invention relates to improvements in an apparatus for removing carbon material and refers more particularly to the removal of carbonaceous substances which have formed in a relatively solid body in the expansion or conversion chambers of oil apparatuses.

Among the important objects of the invention are to provide an apparatus which serves to assist in the breaking up of this 20 carbon body subsequent to the carbon accumulation and thereby facilitate the cleaning of the apparatus.

Fig. 1 is a diagrammatic side elevational view of the apparatus connected in a cracking system.

Fig. 2 is a detail of the hoisting mechanism for removing the chain from the expansion chamber.

Referring to the drawings, heating coil 1 is positioned in the heating chamber of a side fired furnace 2. This coil is connected by transfer line 3 to the expansion or vaporizing chamber 4. This chamber in turn is connected by a vapor line 5 to a 35 dephlegmator 6 into the upper portion of which the oil charging stock is introduced through the line 7. The vapors rising through the dephlegmator pass off through the line 8 and after being condensed in the coil 9 are directed through the line 10 to the receiving tank 11 where they are collected as liquid distillate. The raw oil with what 40 reflux condensate it may collect in the dephlegmation of the vapors in the refluxing column is drawn off from the lower leg 7 of the dephlegmator and is directed through the line 12 to the heating coil 1.

The expansion chamber consists of an enlarged vertically positioned chamber which 50 has upper and lower manhole plates 13 and 14 respectively, which are closed and bolted to form liquid and pressure tight closures when the apparatus is being operated, and which may be opened to permit the accumu-

lated carbon to be removed from the chamber.

The chamber is further equipped with liquid drawoff lines 15 controlled by valves 16 positioned at different heights on the chamber so that as the level of the carbon rises, and clogs each successive drawoff line, the one above may be utilized to remove the heavy unvaporized oil constituents from the chamber. When the carbon has accumulated to an amount above the upper residuum drawoff line, the apparatus should be shut down and the chamber cleaned. In the chamber is positioned a large heavy flexible element such as a steel chain or cable 17, of any desired size and of standard construction, the coils being positioned at the bottom of the chamber while at intervals throughout its length it is hooked or otherwise fastened by means of members shown at 18, to the inner wall of the chamber. By being supported in this manner, it is possible to distribute the flexible element through the carbon body thereby making it easier to disrupt the carbon after formation. The upper end of the cable is hooked as shown at 19 to the upper manhole plate 20.

During operation, the carbon will accumulate and settle upon the lower coils of the chain and as it builds up, the lengths of the cable extending across the chamber will be positioned in the body of the accumulated carbon.

After the apparatus has been shut down for cleaning and the carbon sufficiently cooled to be manually removed, the upper extremity of the cable is passed over the sheave 21 supported by the yoke 22 bolted to the upper flange or manhole plate flange and the chain pulled vertically from the chamber by means of a winch or other mechanism whereby it will be removed successively from the hooks arranged along the sides of the chamber, and with its removal the carbon body will be broken up into pieces which can be readily removed from the chamber.

It is a very difficult matter to remove a carbon formation of this character when it is permitted to accumulate in a solid form, and where there is an unbroken carbon formation, considerable time is necessary to remove the carbon from the system.

By means of the apparatus described, the

carbon accumulation can be readily broken up and removed from the chamber, and the system more readily again put into operation.

5 It is becoming necessary to convert the heavier oils such as fuel oil and other asphaltic base oils which are heavily carbon laden. For this reason it is essential that some provision be made for removing the 10, carbonaceous material from the system as it accumulates in considerable quantities in a relatively short period of time.

I claim as my invention:

15 1. In an apparatus of the character described, the combination of an enlarged reaction chamber wherein carbon is precipitated and collected during the conversion of oil, of a flexible metal member releasably supported within said reaction chamber at 20 a plurality of different vertical points there-

of and adapted to be distributed vertically throughout the deposited carbon collected in the chamber and to be withdrawn from said chamber to disrupt the entire mass of such deposited carbon.

2. In an apparatus of the character described, the combination with an enlarged reaction chamber, a substantial portion of which is adapted to be filled with precipitated carbon collected during the conversion 30 of oil, of a flexible metal member releasably supported in said chamber, said element having a substantial portion thereof vertically disposed in the portion of such chamber where the carbon collects and adapted to be positioned vertically throughout such carbon to disrupt the same when withdrawn from the chamber.

LYMAN C. HUFF.
